Inventor;
William ^{de} Thurber

UNITED STATES PATENT OFFICE.

WILLIAM THURBER, OF OLEAN, NEW YORK.

IMPROVEMENT IN LIFTING-JACKS.

Specification forming part of Letters Patent No. 40,867, dated December 8, 1863.

To all whom it may concern:

Be it known that I, WILLIAM THURBER, of Olean, in the county of Cattaraugus and State of New York, have invented new and useful Improvements in Lifting-Jacks, and the following is a clear and exact description of the same, reference being had to the accompanying drawings, making a part of this specification, in which—

Figure 1 shows a side elevation. Fig. 2 represents a face view. Fig. 3 is an under side view.

My invention consists in the arrangement of truck-wheels, a spring-shoe, and calks, on the under side of a bed-piece, for the purpose of moving and easily placing the lifting-jack in position and anchoring the same firmly by the operation of the lifting; also in the arrangement and combination of the hanging rack, the stirrup, supporting-spring, and notched lever for changing the fulcrum.

To enable others skilled in the art to make and use my invention, I will describe it more fully, referring to the drawings and to the letters of reference marked thereon.

My improvements are designed more particularly for what is usually called a "wagon-jack," but may be applied to a lifting-jack for any other purpose. I make my bed-piece A of plank of convenient length and suitable width to frame in near the front end two vertical posts, B B, the space between them being of sufficient width for the slide or lifting-post C, which has its support in the metal guides D D. The face of the lifting-post C, I plate with metal d, and have a series of pin-holes, c c c c c, in which to insert a pin, f, to accommodate the height of the article to be lifted. On the rear side of the posts B, at the top, is a brace of metal, b, on the center of which is secured a pendent rack, a series of notches or hooks, a a, onto which a link or stirrup j, through which the lever E passes, and to which the stirrup j is attached, the stirrup being fitted to hook onto the notches a so that, by the action of the supporting-spring e, which is secured to the rear end of the bed-

piece A, the forward end of the spring e being and operating in the space between the vertical posts B B, the lever E is easily elevated or depressed, so that the notches i i i near the end of the lever will catch the toe-piece g, on the lower end of the lifting-post C, which, by carrying in or out the fulcrum of the lever, is changed for lifting a greater or lesser weight, as required. There is a small spring, b, operating against the link or stirrup j to make it catch onto the rack a a. Near to the rear end of the bed-piece A is a standard, F, it having a series of holes, o o o, to insert a pin p to hold the lever and weight at rest. Just in front of the vertical posts B B, on each side of the bed-piece A, I place two truck-rollers, II. Near the axle of the rollers on the under side I secure a spring shoe or slide h, which extends back to the rear end of the bed piece A, and when pressed down the spring-shoe h lies in between two calks or short sharp-pointed spikes k k.

To place the lifting-jack and operate the same, take hold of the extended portion of the lever E, which, when it is in its place, will serve as the handle to move and place the jack up to the axle, or anything you wish to lift. Then by bearing down the lever you force the shoe between the pivots, so that they take hold of the ground or floor and hold the machine from moving on the rollers.

Having thus fully described my improved lifting-jack, what I claim as my invention, and desire to secure by Letters Patent, is—

1. The combined arrangement of the truck-wheels I I, the spring-shoe h, and pointed spikes k k, operating in the manner as and for the purposes herein set forth.

2. The combination of the hanging rack a, the stirrup j, the supporting-spring e, and the lever E, with its notches i i i, for changing the fulcrum to get more or less power on the lever, in the manner herein specified.

WILLIAM THURBER.
